UNITED STATES PATENT OFFICE.

JOSEPH ROSS, OF VINCENNES, INDIANA.

HAY-BALER.

SPECIFICATION forming part of Letters Patent No. 662,028, dated November 20, 1900.

Application filed February 5, 1900. Serial No. 4,038. (No model.)

To all whom it may concern:

Be it known that I, JOSEPH ROSS, a citizen of the United States, residing at Vincennes, in the county of Knox and State of Indiana, have 5 invented certain new and useful Improvements in Hay-Balers; and I do hereby declare the following to be a full, clear, and exact description of the invention, such as will enable others skilled in the art to which it appertains to make and use the same.

This invention relates to improvements in hay-balers, and is particularly designed to be used on farms and is so constructed as to be portable, and has for one of its objects to provide an efficient hay-press having interchangeable parts and so constructed as to be knocked down and packed for storage or shipment, and the parts herein employed correspond in many features to those described in my Patent No. 20 632,539, dated September 5, 1899.

A further object of my invention is to provide an efficient hay-press which is operated by hand-power and which is designed to press two bales at a time; and consequently it is 25 my object to construct the means of operating my press so as to gain as much power as is consistent with the strength of the press and the purpose for which it is constructed.

A further object of my invention is in forming the follower of two T-shaped portions united in the center to a middle portion, which is screw-threaded, the outer ends of the said T-shaped pieces being formed to carry anti-friction-roller wheels, the wheels traveling on 35 a longitudinally-guiding brace-rod sunk in the sides of the press.

The invention consists in constructing a wagon-like box of separate pieces, dividing it longitudinally through the center, placing 40 therein a spindle screw-threaded part of its length, and a traveling cross-head screw-threaded to fit said spindle, said cross-head being formed with T-shaped pieces to carry anti-friction-roller wheels, the sides of the 45 press being provided with longitudinally-guiding brace-rods sunk into said sides for the wheels to travel on, said rods acting at the same time as an efficient brace for the entire press, guarding against the spreading of the 50 sides and the collapse of the ends.

This invention also relates to other novel features of construction, which will be here-

inafter described, and particularly pointed out in the claims.

Referring to the drawings, Figure 1 is a 55 perspective view of my baling-press in an open position. Fig. 2 shows a top plan view. Fig. 3 is a transverse section of the follower, showing the antifriction-roller wheels and the longitudinally-guiding brace-rods sunk into 60 the sides of the press. Fig. 4 is a detail view of my pawl-and-ratchet device for operating the press. Fig. 5 is an edge view of the same, showing handle attached. Fig. 6 is a perspective view of the cross-head, showing the 65 T-shaped end and antifriction-roller wheels.

Referring to the drawings by numerals, 1 indicates the sides of my hay-press, and 2 the ends.

3 is the follower, and 4 the threaded spindle. 70

5 indicates the longitudinally-guiding brace-rods, carried in grooves 6.

7 indicates the T-shaped cross-head, and 8 the antifriction-roller wheels carried thereby.

9 represents the ball-bearings, in which the 75 threaded spindle 4 revolves.

10 indicates the large gear-wheels, attached in any suitable manner to the threaded spindle 4 and meshing with the pinion 11.

12 indicates the yoke-straps, in which the 80 pinion 11 is journaled, said straps being offset at a and hold the wheels in mesh, said straps 12 carrying the pinion on the inside, between the straps and the ends 2, and ratchet and pawl on the outside, said ratchets and 85 pawls being attached to the pinion-shafts on the outside of said straps 12, said straps being secured and braced to the press by means of the longitudinally-guiding brace-rod 5, as shown in Fig. 2, and the ordinary bolts 13 14 90 indicate the outer casings of my pawl-and-ratchet device, and 15 is the ratchet-wheel, provided with a square central opening 16, said wheel revolving in recesses 17 of the casings 14, said casings being provided with recesses a little deeper than half the width of the ratchet-wheel.

18 indicates the pawl, secured in the groove 19 of the outer casings 14 and arranged so as to engage the teeth 20 of the wheel 15 by means 100 of the coil-spring 21.

22 represents bolts which secure the outer casings 14 to each other and to the handle-lever 23. The operating means, together with

wheel, pinion, and strap, are duplicated at each end of the press.

Having described the several parts of my invention, its operation is as follows: All the 5 parts of the baling-press are placed together by first placing the bottom in a horizontal position, then setting up the sides carrying the longitudinally-guiding brace-rods 1, then placing the lower half of the central partition in 10 which the threaded spindle revolves longitudinally in the box, then the screw-threaded spindle in position centrally on the lower half of said partition, the cross-head being previously placed on the spindle, then putting 15 the ends 2 over the ends of the spindle and pushing them in place, then adjusting the ball-bearing on the spindle, then putting the gear-wheels on said spindle and the pinions on journals in the ends of the press 2, and 20 then attaching the metal yoke-strap to the ends 2 and over the longitudinally-guiding brace-rods and on the outside of the gear-wheels and pinions. The pawl and ratchet is then attached to the pinion-shaft. The 25 upper half of the central partition is then put in place over the lower half. The doors are then attached to the sides 1 of the press, and the press is now ready for operation. When the follower is at either end of the press, 30 the other apartments are filled with hay. There is a metal strap for holding the operating means, as described, at both ends of the press, said straps being held to said ends by means of the longitudinally-guiding brace-rods, so that the press can be worked by two 35 men. When the lever-handle is raised, the pawl passes over the ratchet-teeth; but when said handle is pushed down the pawl engages the teeth and turns the wheel. This wheel 40 is detachably attached in any suitable manner to the shaft of the small gear-wheel, as by means of a pin, and turns said wheel, which meshes with the larger one. Said larger gear-wheel is securely attached in any suitable 45 manner to the threaded spindle and turns said spindle. The follower or cross-head is provided with a central threaded opening, in which the threaded spindle revolves. When 50 said spindle is turned by means of the operating mechanism, it moves the follower and

presses the hay into bales. After the said bales are properly wired and before they are taken out the other end of the press on either side of the threaded spindle is filled, the threaded spindle is turned the reverse, and the follower moves in the opposite direction, pressing the hay in the two other compartments last filled. The antifriction - roller wheels travel on the longitudinally-guiding brace-rods, guiding the follower or cross-head and preventing the threaded spindle from buckling or bending when there is an unequal strain put on the screw from one side or the other of the press caused by more or less hay being placed in one side than the other. 65

I do not wish to limit myself to the exact construction herein set forth, but consider myself entitled to any change or modification within the spirit and scope of my invention. 70

Having thus described and set forth the operation of my invention, what I claim as new, and desire to secure by Letters Patent of the United States, is—

1. In a hay-press, the combination with the sides of the press provided with longitudinal grooves, of longitudinally guiding brace-rods, carried in said grooves, of a follower provided with antifriction - roller wheels, adapted to travel on said rods, the ends of the press braced by said rods, metal straps adapted to be securely held by said rods for the purpose of holding the operating mechanism, and means for operating the follower, substantially as described. 75

2. The combination in a hay-press, of the ends and grooved sides, longitudinally-bracing guide-rods set in said grooved sides, and bracing said ends, metal straps secured by said rods at both ends of the press, said straps carrying the gear-wheels between the straps 90 and the press, and a ratchet-and-pawl mechanism on the outside of said straps, substantially as shown and described.

In testimony whereof I affix my signature in presence of two witnesses.

JOSEPH ROSS.
